UNITED STATES PATENT OFFICE.

HARRY M. YOUNG, OF WEBSTER GROVES, MISSOURI, ASSIGNOR TO CALUMET STEEL COMPANY, OF CHICAGO, ILLINOIS, A CORPORATION OF ILLINOIS.

CLIP-BENDING DIE.

Application filed June 23, 1927. Serial No. 200,868.

This invention relates to a die for clinching the prongs of U-shaped metal clips about the side edges of rolled metal fence posts for securing anchor plates thereto.

With dies as heretofore used difficulty has been experienced in the prongs of the clips breaking off during the clinching operation, especially with posts having rearwardly inclined flanges extending along the sides of the post. With these posts in particular the die action was such that these flanges were distorted to such an extent at the clips as to cause the hard metal posts to produce a shearing action on the softer metal clips.

The main object of my invention is to overcome this difficulty by providing a die which will effectively clinch the prongs of the clips over the flanged edges of the posts without shearing the clips as heretofore.

A further object of my invention is to provide a die which is automatic in its action after being set in motion and which will firmly and rigidly clinch the prongs of the clips over the side edges of the posts to effectively secure the anchor plates thereto.

The invention consists further in the matters hereinafter described and claimed.

In the accompanying drawings—

Fig. 1 is a top plan view of the lower member of my improved die;

Fig. 2 is a vertical sectional view taken on line 2—2 of Fig. 1, showing both the upper and lower members of the die in separated relation;

Figs. 3 and 4 are similar views showing how the die operates to clinch the prongs of a clip over the side edges of a post in securing an anchor plate thereto;

Fig. 5 is a vertical sectional view taken on line 5—5 of Fig. 1 to show a detail of construction;

Fig. 6 is a horizontal sectional view taken on line 6—6 of Fig. 2;

Figs. 7 and 8 are front and side views, respectively, of the lower portion of a rolled metal studded fence post having an anchor plate fastened thereto by a clip which is clinched against the post by the die of my invention; and

Fig. 9 is a horizontal sectional view, taken on line 9—9 of Fig. 7, showing the clip before its prongs are clinched over the side edges of the post.

The die of my invention comprises a base plate 1 which is bolted or otherwise rigidly

secured to the bed of a punch press. The base 1 is provided in its upper side with a channel 2 which extends clear across the base from front to rear and in which is tightly fitted a hard tool steel insert 3. The latter extends the full length of the channel 2 and has its upper surface flush with the top surface of the base 1, as shown in Fig. 2. Two substantially parallel steel bars or strips 4, 4 are secured on the top surface of the base 1 along the side edges of the insert 3. These strips 4 extend substantially half way across the base 1 from its rear edge 5 and provide stops for the anchor plate 6 so as to center or position its fastening clip 7 with respect to the bending and clinching dogs 8, 8 of the die when inserting the assembled post 9, plate 6, and clip 7 into the die from the front edge 5^a of the base 1. When so positioned, the body portion 7^a of the clip 7 lies flatwise against the upper surface of the insert 3 with the prongs 7^b of the clip extending vertically upward between the dogs 8, 8, as shown.

The post 9 is of the rolled steel type, preferably T-shape in cross-section, and has a row of studs or lugs 10, 10 extending along the center of the bead or front flange 9^a of the post the full length thereof, as indicated in Figs. 7 and 8. These studs or lugs 10 are produced in the rolling of the post and project outward from the front flange 9^a from a low rib 11 extending along the length of the post and produced in the rolling thereof. The insert 3 has a shallow groove 12 extending lengthwise thereto to receive the lugs or studs 10 and thus permit the body portion 7^a of the clip to lie against the insert 3, as shown.

Guide blocks 13, 13 are secured on the upper side of the base 1 on opposite sides of the insert 3. These blocks are oppositely disposed and are cut away on their under sides adjacent the insert 3 to provide recesses 14, 14 to receive the outer side portions of the anchor plate 6 and hold the plate from tipping during the bending and clinching operations of the die on the prongs of the clip 7. As shown in Figs. 2, 3, and 4, the side edges of the plate 6 where they extend into the recesses 14 engage the adjacent walls of the same. This holds the plate 6 against lateral displacement when between the blocks 13, and thus the clip 7 is centered between the dogs 8. The ends of the recesses 14 and the ends of the strips 4 are shaped to conform to

the contour of the portions of the anchor plate 6 engaged thereby, so as to automatically adjust and center the plate with its clip 7 between the dogs 8 on inserting the assembled post, plate, and clip into the die from its front edge 5^a. The lower or pointed end portion of the post 9 at this time lies between the strips 4 and these are spaced apart for that purpose.

10 Slidably mounted in the guides 13 are plungers 15, 15 having their outer ends rounded and acted upon by the lower ends of vertically disposed levers 16, 16, which are fulcrumed at 17, 17 to upwardly extending lugs 15 or ears 18, 18 at the outer ends of the guides. The plungers 15 are provided with outwardly projecting rods 19, 19, which extend through passages 20, 20 in the lower ends of the levers 16, as shown in Fig. 3. The rods 19 extend 20 outward beyond the levers 16 and there carry coiled expansion springs 21, 21, which hold the plungers 15 against the lower ends of the levers 16, 16 and return the plungers and the levers to their normal positions after the 25 clinching operation of the die. The springs 21 are interposed between washers 22, 23 on the respective rods, with the washers 23 held by the springs against nuts 24 on the outer ends of the rods, and with the washers 22 held 30 by the springs against the outer sides of the levers.

35 The dogs 8, 8 are at the inner ends of the plungers 15 and normally project beyond the inner ends of the guides 13. The dogs are pivoted to their respective plungers 15 by horizontal pivot pins 25 so that the dogs may have up and down movements at the proper time. To permit of these movements, the upper edge of each dog 8 on the outer side of the 40 pivot 25 is beveled off or inclined, as at 26, as clearly shown in Figs. 3 and 4. When the dogs 8 are projected far enough out of the guides 13 to be in positions to clinch the prongs of the clip 7, the straight upper edges 45 27 of the dogs inside of the inclines 26 lie outside of the guides 13 so that the dogs may be forced downward to clinch the prongs of the clip 7 by the ram 28, which is carried by the vertically reciprocable plunger or head 29 of the press. When the dogs 8 are retracted back 50 into the guides 13 through the action of the springs 21 on the plungers, the upper straight edges 27 of the dogs are then within the guides 13 and the dogs are held from pivotal movements. The dogs 8 and plungers 15 are 55 preferably made rectangular in cross-section, and the sideways in the guides 13 are similarly shaped so as to hold the dogs and the plungers from turning, as indicated in Fig. 5.

60 Screwed or otherwise secured to the under side of the plunger 29 is a plate 30, which forms the upper member of my improved die. This plate 30 extends on opposite sides of the plunger 29 and there carries rollers 31 which 65 are designed to operate on the upper inclined

or beveled ends 32 of the levers 16. These inclines terminate in vertical notches 33, 33 on the inner sides of the levers 16 and into which notches the rollers 31 pass after leaving the inclines 32.

70 The structure shown and described operates as follows. The anchor plate 6 is first applied to the post 9 and the prongs 7^b of the clip 7 are inserted through openings 6^a, 6^a in the plate with the prongs of the clip extending upward 75 on opposite sides of the post. The assembly is then inserted endwise into the die between the dogs 8, 8, which are retracted at this time by the springs 21 into the positions shown in Fig. 2 so that the upright prongs of the clip 80 may pass between them. In inserting the assembly into the die, the side portion of the anchor plate 6 enter the channels 14, and the plate is stopped by contact with the strips 4 with the upwardly extending prongs 7^b between the dogs and in position to be operated 85 upon by them.

Power is then applied to the press and the plunger 29 is moved downward, carrying therewith the rollers 31 into engagement with the inclined surfaces 32 at the upper ends of the levers 16 which at this time are extending vertically upward. A continued downward movement of the plunger 29 causes the rollers 31 to move down the inclines 32 of the levers 95 and move the lower ends of the latter inward, thereby moving the plungers 15 inward and moving the dogs 8 toward each other to bend the prongs 7^b of the clip 7 inward and over the side edges of the front flange 9^a of the post, as 100 shown in Fig. 3. When this has occurred, the rollers 31, 31 then pass over the lower ends of the inclines 32 and continue down into the notches 33, 33 and hold the levers 16 from being brought back to their normal upright positions by the springs 21. The notches 33 are deep enough so that the head 29 in its continued downward movement may bring the ram 28 against the inner ends of 105 the dogs 8, 8 and force them downward toward the post and the plate. The lower portions of the dogs are shaped so as to force the bent over prongs of the clip down into tight engagement with the rear side of the front flange of the post on opposite sides of its rear 110 or back web 9^b, as shown in Fig. 4, and thereby clinch the clip against the post and tightly secure the anchor plate thereto. After this has been accomplished, the head 29 starts upward on its return movement and the ram 28 is 115 withdrawn from contact with the dogs. As soon as the rollers 31 leave the notches 33, the levers 16 are then free to be swung into their normal upright positions by the springs 21, the plungers 15 and dogs 8 being retracted from the post into the guides 13, as shown in Fig. 2. The die is then in position to receive another post for fastening an anchor plate 120 thereto by a clip 7.

The passages 20 in the levers 16 are made

- large enough so that the levers may swing back and forth without binding on the rods 19. The lower inner ends of the dogs 8 are pointed, as at 8^a, so as to clinch the prongs 5 7^a about the rearwardly inclined flanges 9^a which are provided at the side edges of the post, as shown in the drawings. With this arrangement, the flanges 9^a at the sides of the post are not acted on to be bent out of 10 position or distorted to have a shearing action on the softer metal clip as heretofore. The ram 28 is clamped to the head 29 of the press by a fastening block 34 and screws 35, as shown in Fig. 6. The ram has a shank 36, 15 which is engaged by the block 34, as shown. Where the dogs 8 are pivoted to their respective plungers 15, the latter are bifurcated or slotted, as at 37, to receive tongues 38 on the dogs, as shown in Fig. 1.
- 20 My improved die is simple in construction and operation and positive in its action. It effects a rigid fastening of the anchor plate to the post by clinching the prongs of the clip down against the rear side of the post 25 without shearing off the clips as heretofore.
- The details of structure shown and described may be variously changed and modified without departing from the spirit and scope of my invention.
- 30 I claim as my invention:
1. A device of the character described, comprising a base adapted to support a metal fence post with its anchor plate and clip, with the clip against the base and having its prongs extending upward through the plate on opposite sides of the post, dogs supported by the base on opposite sides of the post, means for first moving the dogs toward each other for bending the prongs of the clip inward over the side edges of the post, and means for thereafter forcing the dogs downward toward the post for clinching the bent over prongs of the clip against the rear side of the post. 35
  - 45 2. A device of the character described, comprising a base adapted to support a metal fence post with its anchor plate and clip, with the clip against the base and having its prongs extending upward through the plate on opposite sides of the post, dogs supported by the base on opposite sides of the post, means including a cam action for first moving the dogs toward each other for bending the prongs of the clip inward over the sides of the post, and means for thereafter forcing the dogs downward toward the post for clinching the bent over prongs of the clip against the rear side of the post. 50
  - 55 3. A device of the character described, comprising a base adapted to support a metal fence post with its anchor plate and clip, with the clip against the base and having its prongs extending upward through the plate on opposite sides of the post which has rearwardly extending inclined flanges along 60
- its said side edges, dogs mounted on the base on opposite sides of the post, means for first moving the dogs toward each other for bending the prongs of the clip inward over the side edges of the post, and means for there- 70 after forcing the dogs downward toward the post for clinching the bent over prongs against the rear side of the post, said dogs having pointed ends to clinch the prongs around the inclined flanges along the sides 75 of the post.
4. A device of the character described, comprising a base adapted to support a metal fence post with its anchor plate and clip, with the clip against the base and hav- 80 ing its prongs extending upward through the plate on opposite sides of the post, guides on the base on opposite sides of the post, plungers slidably mounted in said guides, dogs pivoted to the inner ends of the plung- 85 ers, means acting on the outer ends of the plungers for moving the dogs toward each other for bending the prongs of the clip inward over the side edges of the post, and means for forcing the dogs downward toward 90 the post for clinching the bent over prongs of the clip against the rear side of the post.
5. A device of the character described, comprising a base adapted to support a metal fence post with its anchor plate and clip, with the clip against the base and having its prongs extending upward through the plate on opposite sides of the post, guides on the base on opposite sides of the post and having rectangular slideways, plungers fit- 95 ting in said slideways, dogs pivoted to the inner ends of the plungers for vertical movement, means acting on the plungers for moving the dogs toward each other for bending the prongs of the clip inward over the side edges of the post, and means for forcing the dogs downward toward the post for clinching the bent over prongs against the rear side of the post, said dogs having in- 100 clined surfaces which when free of the guides 105 permit the dogs to be forced downward to clinch the prongs.
6. A device of the character described, comprising a base adapted to support a metal fence post with its anchor plate and clip, with the clip against the base and having its prongs extending upward through the plate on opposite sides of the post, guides on the base on opposite sides of the post, dogs slidably mounted in said guides, means for first mov- 110 ing the dogs toward each other for bending the prongs of the clip inward over the side edges of the post, and means for thereafter forcing the dogs downward toward the post for clinching the bent over prongs of the clip against the rear side of the post, said guides 115 serving to hold the dogs against downward movement during the bending of the prongs by the dogs inward over the side edges of the post. 120
- 125
- 130

7. A device of the character described, comprising a base adapted to support a metal fence post with its anchor plate and clip, with the clip against the base and having its prongs extending upward through the plate on opposite sides of the post, guides on the base on opposite sides of the post, plungers slidably mounted in the guides, rods secured to the outer ends of the plungers and extending outward therefrom, dogs pivoted to the inner ends of the plungers, levers pivoted on the guides at the outer ends of the plungers, means acting on the levers to move the dogs toward each other for bending the prongs of the clip inward over the side edges of the post, a ram for thereafter acting on the dogs for clinching the prongs against the rear side of the post, and springs means for returning the levers, dogs, and plungers to their normal positions in the upward movement of the ram out of engagement with said dogs.
8. A device of the character described, comprising a base adapted to support a metal fence post with its anchor plate and clip, with the clip against the base and having its prongs extending upward through the plate on opposite sides of the post, guides on the base on opposite sides of the post, dogs slidably mounted in said guides, upright levers pivoted to the guides and having inclines and notches at their upper ends, a movable member having rollers to engage the inclines of the levers for moving the dogs inward toward each other for bending the prongs of the clip inward over the side edges of the post, and a ram carried by said member and operating against the dogs to clinch the bent over prongs of the clip against the rear side of the post as the rollers are moved downward into the notches of the levers.
9. A device of the character described, comprising a base adapted to support a metal fence post with its anchor plate and clip, with the clip against the base and having its prongs extending upward through the plate on opposite sides of the post, plungers slidably mounted in said guides and having outwardly extending rods, upright levers pivoted on the guides at the outer ends of the plungers, dogs pivoted to the inner ends of the plungers, a movable member arranged above the base and adapted to act in its downward movement on the levers to move the dogs toward each other for bending the prongs of the clip inward over the side edges of the post, a ram carried by said member and engageable with the inner ends of the dogs for clinching the bent over prongs of the clip against the rear side of the post, and coiled springs on the rods for holding the levers against the plungers and for returning the dogs, plungers, and levers to their normal positions in the upward movement of the ram out of engagement with the dogs.
10. A device of the character described, comprising a base adapted to support a metal fence post with its anchor plate and clip, with the clip against the base and having its prongs extending upward through the plate on opposite sides of the post, guides on the base on opposite sides of the post, plungers slidably mounted in the guides, rods secured to the outer ends of the plungers and extending outward therefrom, dogs pivoted to the inner ends of the plungers, upright levers pivoted to the guides at the outer ends of the plungers and having passages for the rods to pass through, said levers having inclines and notches at their upper ends, a vertically movable member above the base and having rollers to engage the inclines of the levers for moving the dogs toward each other, a ram carried by said member for forcing the inner ends of the dogs downward as the rollers enter the notches in the levers in the downward movement of said member, and coiled springs on the rods for holding the levers against the plungers and for returning the plungers, levers, and dogs to their normal positions as the ram moves upward out of engagement with the dogs.
11. A device of the character described, comprising a base adapted to support a metal fence post with its anchor plate and clip, with the clip on the base and having its prongs extending upward through the plate on opposite sides of the post, dogs supported by the base on opposite sides of the post, means for first moving the dogs toward each other for bending the prongs of the clip inward over the side edges of the post, means for thereafter forcing the dogs downward toward the post for clinching the bent over prongs of the clip against the rear side of the post, and stop means on the base for centering the clip with respect to the dogs.
12. A device of the character described, comprising a base adapted to support a metal fence post with its anchor plate and clip, with the clip against the base and having its prongs extending upward through the plate on opposite sides of the post, guides on the base on opposite sides of the post, dogs slidably mounted in said guides, means for first moving the dogs toward each other for bending the prongs of the clip inward over the side edges of the post, and means for thereafter forcing the dogs downward toward the post for clinching the bent over prongs against the rear side of the post, said guides having recesses at the base to receive the side portions of the anchor plate for holding said plate against tipping and lateral displacement during the operation of the dogs on the prongs of the clip.
13. A device of the character described, comprising a base adapted to support a rolled studded metal fence post with its anchor plate and clip, with the clip on the base and having its prongs extending upward through the plate on opposite sides of the post, dogs

on the base on opposite sides of the post, means for first moving the dogs toward each other for bending the prongs of the clip inward over the side edges of the post, and 5 means for thereafter forcing the dogs toward the post for clinching the bent over prongs of the clip against the rear side of the post, said base having a groove running across the same to receive the studs of the post so that the clip may lie against the base during the 10 clinching operation of the dogs on the clip.

In testimony whereof I affix my signature.

HARRY M. YOUNG.
